UNITED STATES PATENT OFFICE.

JOSEPH PHILIP KERR, OF SAN JACINTO, CALIFORNIA.

DESIGN FOR AN END-STICK FOR LOCKING UP TYPE.

SPECIFICATION forming part of Design No. 19,332, dated October 1, 1889.

Application filed August 16, 1889. Serial No. 321,023. Term of patent 14 years.

To all whom it may concern:

Be it known that I, JOSEPH PHILIP KERR, a citizen of the United States, residing at San Jacinto, in the county of San Diego and State 5 of California, have invented a new and original Design for End-Sticks for Locking Up Galleys of Type, of which the following is a specification.

The invention relates to a new and original 10 design for end-sticks for locking up galleys of type.

Figure 1 is a perspective view of an end-stick showing my design. Fig. 2 is a side view of the same.

15 The leading feature of the design is the form of the spring and the inner side of the base.

A designates the base, having a straight flat outer side a , and the inner face having sides 20 a' inclined toward each other and terminating in the concave portion a^2 .

B designates a spring having the ends b bent outward and a portion b' intermediate of its ends curved inward and resting in the concave portion a^2 of the inner side a' of the 25 base A.

What I claim is—

The design for end-stick herein shown and described, consisting of the base A, having the flat outer face, and the inner face having 30 inclined sides terminating in the concave portion a^2 , and the spring having its ends turned outward, and the portion b' intermediate of the end curved inward, substantially as described.

In testimony that I claim the foregoing as my own I have hereto affixed my signature in presence of two witnesses.

JOSEPH PHILIP KERR.

Witnesses:

E. J. LOGSDON,
GEO. WEBER.
